UNITED STATES PATENT OFFICE.

CHARLES A. HONECKER, OF CHICAGO, ILLINOIS, ASSIGNOR TO AUTOMATIC UTILITIES CO., A CORPORATION OF ILLINOIS.

LOOSE-LEAF INDEX.

1,148,680.

Specification of Letters Patent. Patented Aug. 3, 1915.

Application filed September 13, 1911. Serial No. 649,200.

To all whom it may concern:

Be it known that I, CHARLES A. HONECKER, a citizen of the United States, residing in the city of Chicago, county of Cook, 5 and State of Illinois, have invented a certain new and useful Improvement in Loose-Leaf Indexes, of which the following is the specification.

My invention relates to that class of loose-leaf devices, which are used to single out a predetermined number of cards and elevate them above their normal plane, and has for its object to provide a simple and effectual mechanism for accomplishing this result, and 15 to do away with the severe frictional losses, caused by the pressure of the lifting bar against the end of the containing case.

My means for accomplishing the foregoing result may be more readily understood 20 by having reference to the accompanying drawings, which are hereunto annexed and are a part of this specification, in which:

Figure 1 is a side elevation of a loose-leaf index box equipped with my invention, 25 part of the side wall being broken away for the purpose of showing the interior construction. Fig. 2 is a top or plan view of the same. Fig. 3 is a cross section taken on line *xx*. Figs. 4 and 5 are detailed views, showing parts of the mechanism.

Similar reference numerals refer to similar parts throughout the entire description.

As shown in the drawings, 1 is the containing case, which is provided with a number of loose-leaves 2, the outer ends of the latter resting upon the members 3, which are located in the lower part of the containing case 1. A plurality of rods 4 are mounted in the lower part of the containing case 40 and these rods are held suspended by cords or wire cables 5; the end 6 of the cord or wire 5 passing through the end 7 of the rod 4 runs over a small grooved pulley 8, which is rotatably mounted upon a shaft 9, whence it passes over a grooved pulley 10, rotatably mounted upon a shaft 11. Thence it travels to and over a grooved pulley 12, which is rotatably mounted upon a shaft 13, when it passes through the bar 4, a stop 14 being secured to the wire or cord 5, to cause its movement to carry the rod 4 upward. The cord then passes around the grooved pulley 15 rotatably mounted upon a suitable shaft 16 and has its end 17 secured in any convenient manner to a rod 18, the upper part

of which is provided with a round disk or indicator, the several indicators having upon their faces suitable characters such as the days of the month, the letters of the alphabet, etc.

In order to permit of the insertion of a larger number of disks or pushbuttons 19 another series of rods 20 is provided adjacent the rods 18, which is also provided with indicators or disks 21. These rods have a cord 35 similar to the cord 5, which extends through the grooved pulley 22 adjacent the grooved pulley 15, whence it passes through one of the bars 4, a stop 27 similar to the stop 14 being provided, the wire or cord 35 65 then passing over a grooved pulley 24, which is mounted upon the shaft 13 adjacent to the grooved pulley 12, whence it passes over a grooved pulley 25, mounted upon the shaft 11 adjacent to the grooved 70 pulley 10, whence it passes up and over a grooved pulley 29, mounted upon a shaft 9, adjacent the grooved pulley 8, the end of the cord secured to the end of the bar 4 in any suitable or desired manner. As shown 75 in Fig. 2, the shaft 9 is broken off at 30 so as to show this arrangement. The same construction is followed for each alternate bar 4 entirely across the entire containing case, it being apparent to persons skilled in the 80 art that a description of two of these is sufficient to construct the entire box.

Upon the bottom of the cards 2 are printed a plurality of numerals or letters corresponding to the characters on the indicators 19 and 21. A metal tab 28 is provided, the lower end 26 of which is adapted to rest in the groove formed in the upper surface of the bars 4, the upper part of the said metal tab being adapted to clamp the lower 85 edge of one of the cards or loose leaves 2.

The operation of the device is as follows: The operator places the metal tab upon those cards which he wishes to cause to be elevated above their normal plane at the characters corresponding to the disk character on the indicators 19 and 21. For example, if he wishes to ascertain how much a certain firm owes, even if the bills are not due, if that firm name begins with A, he can by 100 pressing the indicator bearing the letter A, elevate all of the cards containing that firm's account through the medium of the cord or wire and the bar 4, as the elevation of this bar will cause the engagement therewith of 105 110

the end 26 of the metal tabs and these will in turn elevate the cards above their normal plane without disturbing the remainder of the cards in the containing case.

- 5 It will be apparent that by utilizing this construction that all of the friction is done away with save that existing between the surface of the cards, and that caused by their contact with the side walls of the containing case 1, aside from the very slight friction necessary in rotating the grooved pulleys upon the respective shafts.
- 10

Having described my invention, what I regard as new and desire to secure by Letters Patent is:

- 15 1. A device of the character described comprising the combination with a containing case, of a plurality of loose leaves in the said case, a plurality of detachable metal pins on the lower edge of said leaves, a plurality of rising rods, adapted to engage said pins, a plurality of grooved pulleys for each of the rising rods, a plurality of shafts upon which said pulleys rotate, a plurality of indicators and a plurality of vertical rods attached thereto, one for each of the rising rods, a flexible connection attached to each end of each of the rising rods and to the respective vertical rod, said connection passing over the grooved pulleys for the purpose set forth, substantially as described.
- 20

- 25 2. A device of the character described, comprising the combination with a containing case, of a plurality of loose leaves in the said case, a plurality of detachable metal pins on the lower edge of said leaves, a plurality of rising rods adapted to engage said pins, a plurality of grooved pulleys for each of the rising rods, a plurality of shafts upon which said pulleys are rotatably mounted, a plurality of indicators and a plurality of vertical rods attached thereto, one for each
- 30

35 of the rising rods, a flexible wire attached to each of the rising rods and to the respective vertical rod, said wires running over said pulleys, whereby the downward movement of an indicator operates to elevate the respective rising rod.

40 3. A loose-leaf device comprising a case containing a plurality of loose-leaves, a plurality of metal pins secured on the lower edge of the said leaves, a plurality of horizontal rods adapted to engage said pins, a series of sheaves for each of the horizontal rods, a plurality of shafts upon which said sheaves are rotatably mounted, a plurality of vertical rods, having indicators at their upper end in number corresponding to the horizontal rods, a flexible wire which passes over the said series of sheaves and through the forward end of each horizontal rod, a 45 detent secured to each of said wires, which engages said rod, one end of the said wires being attached to the respective vertical rod, whereby the downward movement of an indicator operates to elevate the respective horizontal rod.

45 4. A device of the character described, comprising a containing case, a plurality of loose leaves therein, a plurality of rising rods, means carried by said loose leaves and adjustable longitudinally thereof, which are engaged by said rising rods, a plurality of vertical rods having indicators at their upper ends, and a flexible connection, connecting each of said rising rods with the corresponding vertical rod for the purpose set forth.

In witness whereof, I have signed the foregoing specification.

CHARLES A. HONECKER.
